UNITED STATES PATENT OFFICE

LEE P. HYNES, OF ALBANY, NEW YORK, ASSIGNOR, BY MESNE ASSIGNMENTS, TO CONSOLIDATED CAR-HEATING COMPANY, INC., OF ALBANY, NEW YORK, A CORPORATION OF NEW YORK

CAR-DOOR OPERATION

Application filed March 11, 1922. Serial No. 543,079.

For a detailed description of the present form of my invention, reference may be had to the following specification and to the accompanying drawings forming a part hereof, wherein

Fig. 1 is a plan of my apparatus;

Fig. 2 shows the door and operating shaft with the limit switches;

Fig. 3 shows the emergency stop on a larger scale;

Fig. 3^a shows a vertical cross section of Fig. 3;

Fig. 4 shows a modified form of emergency stop;

15 Figs. 5 and 5^a show plan and side views, respectively, illustrating the application of my apparatus to folding doors; Fig. 6 shows a detail of the emergency switch, and

Figs. 7 and 8 are diagrams of the circuits.

20 Heretofore car doors have usually been operated by pneumatic engines, for which electromagnetic controllers have been employed. It is my present purpose to operate car doors directly by electric motors, my devices for 25 that purpose being herein described and claimed.

Referring to the drawing, A represents a car door which, in this case, is a sliding door of any usual design. On the rear edge of the 30 door is a vertical guide a in which travels a roller c on the outer end of a radial operating arm C on a shaft B. As the shaft B is rotated through an arc of 180 degrees, it will cause the door to slide back and forth from 35 its open to its closed position, or vice versa, the roller c moving up or down in guide a according to the angular position of the operating arm. Adjacent to the door is a base-plate K on which the said shaft B is mount- 40 ed in a journal box b. In line with shaft B but separated therefrom is a second shaft B¹ also mounted on base-plate K. On the same base-plate is also an electric motor D, preferably a series motor, which has on its 45 shaft a pinion engaging gear wheel G, while a pinion on the shaft of the gear wheel G drives a second gear wheel H on the aforesaid shaft B¹. On the adjacent ends of the aligned shafts B and B¹ are fixed respectively 50 the radial arms E¹ and E² which normally

occupy the same angular position, the two shafts rotating in unison. As is fully shown in Fig. 3, the arms E¹, E² are embraced between two spring-pressed plates O¹ and O². The springs R¹, R² bear on these respective 55 plates, while a bolt P passes through the back-plates Q¹ and Q² of the respective springs and through the plates O¹, O², also passing through an opening p, formed partly in arm E¹ and partly in arm E². Thus the 60 two arms are held in alignment by the pressure of the springs R¹, R² and will remain in alignment during the ordinary opening and closing of the door. If, however, the door 65 sticks or encounters an obstruction, particularly when a passenger is caught in the door, the springs will yield and the arms will separate, assuming different angular positions. This may occur in either direction of movement of the shafts B, B¹. The arm E¹ carries 70 an insulated spring 3 on which is mounted a contact point 5, while arm E² has a similar spring 4 with a contact point 6. Normally the points 5 and 6 are in contact, but in the event of the separation of the two arms as 75 above described, the points 5 and 6 will also separate and break the circuit passing through them. This circuit is the main motor circuit, the flexible conductors 7 and 8 of said 80 circuit leading to the respective contacts 5 and 6. Since the range of oscillation of the arms is but 180 degrees, these flexible conductors 7 and 8 will maintain the electrical connection of the contact points with the motor circuit, but rings and contacts sliding thereon 85 may be used in place of them, as the art well understands. This emergency circuit-breaker is marked X and may be termed a torsion switch, or stress switch since it responds to the force which the motor continues 90 to exert when the door is blocked. I thus provide that the motor circuit will be broken in the event of such an obstruction of the motor as I have heretofore mentioned, while if necessary the open-circuited motor can be turned backward by pushing back on the door in order to release a passenger or other object which might be accidentally pinched between the door and its jamb. Moreover, 95 since there is now no current on the motor, it 100

will be turned backward by the reaction of the springs R^1 , R^2 until the contacts 5 and 6 come together again and once more close the motor circuit. Then the motor will again start to close the door and will succeed, provided the obstruction has been removed; if not, the circuit will be again broken, as above described, and the operation will be repeated until the obstruction is eliminated and the motor ultimately succeeds in closing the door. This highly desirable action I secure without resort to a shoe on the front edge of the door such as is now required to get a similar protection for the passengers. Such a door-shoe is a cause of expense and trouble, so that its elimination is a marked advance in the art. It should also be observed that I have interposed between the door and the electric motor not only the usual toothed gearing but also the radial arm C which tends to give the door a rising and falling rate of speed following a sine curve for a constant speed of rotation of the shafts B, B¹. By this means I am enabled to use a much smaller motor than would otherwise be required, since at the starting of the door when the load is the heaviest, the motor has an increased leverage on the door and in this manner can gain mechanically by increased speed and small current what would otherwise require a large current and slow motor speed—i. e. a larger motor. Moreover, in stopping the door the motor again has a corresponding increase of leverage, with high speed and a small current which can be readily broken by the limit switch. Thus by combining a rotating arm drive with reducing gear between the arm-shaft and the motor, I secure an advantage both at the starting and at the stopping of the door and with the use of a smaller motor than would otherwise be needed.

In Fig. 4 is shown at X² a modified form of the emergency switch X. In this form the arm E¹ is extended by an insulating disc E³ secured to its outer end on which is pivoted a switch blade E⁴ that normally connects the terminals of the aforesaid wires 7 and 8. On the center of blade E⁴ and insulated therefrom is a block E⁵ which has a flat underside 14 against which bears a bow-spring T secured on the end of arm E². This is the normal condition, the blade E⁴ being thereby held in its connecting position shown in the figure. Two legs 9 and 10 project from block E⁵ through loosely fitting holes in the bow-spring T. When the arms E¹ and E² separate, the block E⁵ and blade E⁴ are rotated until the corner of the side or face 14 comes under the center of the block's pivot; then the block will snap ahead of the spring T and one of its inclined faces 12 will come to rest on the spring T, thereby giving a quick break of the main circuit through wires 7 and 8. This will occur in whichever direction the

separation of the arms takes place, while the engagement of lugs 9 and 10 with spring T will cause the block to snap back into its normal position when the alignment of the arms is restored.

For the operation of folding doors the arrangement of Fig. 5 may be used. The door is composed of four folding panels A¹, A², A³, A⁴. In the framework of the car above the door is mounted a short vertical shaft S with two radial arms C¹ and C² extending therefrom in opposite directions. Arm C² is connected by link C³, to the outer end of lever C⁴ on panel A⁴, while arm C¹ is similarly connected by link C⁵ to lever C⁶ on panel A¹. Loosely mounted on shaft S is a horizontal bevel-gear wheel U which is driven by the motor through a bevel pinion and reduction gearing. Above bevel-wheel U and secured to shaft S is a star-wheel V, the opposite points of which are linked to bevel-wheel U by springs R¹, R². Hence the motor-driven wheel U drives the shaft S through the springs R¹, R². Normally these springs will not yield, but will do so in the event of an obstruction of the doors as heretofore explained, and will thereby operate the emergency switch X³, mounted on wheel U. The switch X³ is shown on a larger scale in Fig. 6, it comprises two switch blades W¹ and W², which are normally held by a spring W⁵ against their two pivotal pins 21 and 22 and in this position they connect the terminals of the wires 7 and 8. From the middle of spring W⁵ a stiff wire W⁴ leads to one point of the star-wheel V, so that a change in the relative positions of the star-wheel and bevel-wheel U will throw spring W⁵ to one side or the other and thereby throw the blades over the dead-center and break the circuit with a snap. This switch X³, like the one X² shown in Fig. 4, has three stable positions closing the circuit in its middle position and opening it in either of its side positions, while it is snapped from any one position to another. In the folding-door arrangement of Fig. 5, I provide a single limit-switch N which is operated by the door at each end of its opening or its closing run. This switch has a sliding rod N³ with projections N⁶ at either end which are alternately hit by the end of lever C⁴ at the end of its stroke. On the end of rod N³ are pivoted the spring-connected blades N⁴ and N⁵ which in the position shown close the door-closing circuit 30 but at the end of the door-closing stroke break the said door-closing circuit 30 and close the door-opening circuit 40, reversing this operation at the end of the door-opening stroke. In Fig. 2 there are two limit switches N¹ and N² operated respectively by the radial arm C in either its door-closing or its door-opening position to break the circuit which produced the ended movement. A spring restores the switch to its circuit-clos-

ing position when the arm C starts away on its reverse stroke, the circuit thus closed at the limit switch being elsewhere broken by the operator's control switch. To one arm of the star-wheel V I connect a rope Z which will extend through the car so that any passenger, by pulling the rope, can open the doors. In Fig. 7 is shown one form of circuit connection for enabling a single operator to control two or more doors from a single station. In this figure, 60 represents a switch drum on which are contact-plates 51 and 52, which, when the drum is turned in one direction, connect stationary point 31 with 32 and 33 with 34; while, when turned oppositely, they connect 41 with 42 and 43 with 44. In the former case a circuit will be established from trolley T, R, through initiating switch 91, resistance 90, fuse 92, torsion-switch X, limit-switch N¹, contact-points 31, 32, wire 45, field-magnet 70 of the motor, wire 46, contact-points 33, 34, wire 47, motor armature 80 to ground. This will start the motor in a direction to close the door A and when the radial arm C reaches the closed-door position it will operate limit-switch N¹ and break the circuit aforesaid. When the switch-drum 60 is turned in the opposite direction, it will establish a similar circuit which will, however, pass through the field-magnet 70 in the reverse direction and will also include limit-switch N², instead of N¹. The motor will then operate to open the door until radial arm C operates limit-switch N² and the door is thereby stopped. The torsion-switch X, it will be observed, is included in both circuits and will be ready to operate on the door-opening as well as the door-closing run of the door. On the contrary, the opening and closing circuits have their individual limit-switch contacts. I have shown on the drum 60 a second set of contact-plates 51 and 52 which will, in like manner, control a second door motor. But while the switch-drum 60 will be common to both motors, each will have its own torsion-switch X and its own individual limit-switch contacts. The two motors will thus be under common control from a single point but will be independent as regards their torsion-switch and limit-switch control.

Other modes of securing similar control may be employed. In Fig. 8 the operator's control is by means of a switch-lever 54 with a blade 53 which in one position connects contacts 38, 39 for—say door opening—and in the opposite position contacts 48, 49 for door closing. If it connects 38, 39 it establishes a circuit from battery J to wire 105 which may serve for all the doors in a car or in an entire train. At each door is a magnet 100, which, being thus energized, breaks connection between points 131 and 132 and closes between points 141 and 142. That establishes a circuit from trolley T, R,

through points 141, 142, motor armature 80, points 131, 132 (of magnet 101), closed contacts of limit-switch N, motor-field magnet 70, torsion-switch X³ to ground. As before described, the motor will then operate the door in the closing direction till stopped by opening of limit-switch N. If switch 54 is turned oppositely to close the connection of points 48, 49, then a similar action will be started by magnets 101. In that case the circuit from the trolley will go through lower contacts 141, 142, motor armature 80, in the reverse direction, upper contacts 131, 132, limit-switch N, which will now have its opposite set of contacts closed, motor field-magnet 70, torsion-switch X³ to ground. If desired, the local doors at the operator's station may be operated by magnets 100 and 101 connected to special contact points 37 which will be engaged by a continued movement of switch-lever 54 after the other doors have been operated. That will be particularly advantageous on the door-closing side, since the operator can leave his local doors open for purposes of observation until the other doors on the car or train are closed.

What I claim as new and desire to secure by Letters Patent is:

1. The combination with a car door, of an electric motor, a rotatable door operating shaft, a gear wheel mounted on said shaft, reducing gearing interposed between and operatively connecting said motor and said wheel, and a radially extended arm carried by an end of said shaft so as to rotate therewith, the free end of said arm having a slideable operating connection with said door.

2. The combination with a car door having a vertical slide thereon, of a door operating shaft positioned at right angles with respect to the plane of travel of said door, a radially extended arm carried by an end of said shaft adjacent to said plane of travel and having its free end connected with said slide, a gear wheel on said shaft back of said radially extended arm, an electric motor, and a reducing gearing connecting said motor and said gear wheel.

3. The combination with a horizontally slideable door, of a horizontally mounted door operating shaft arranged with one end adjacent the plane of travel of said door, a radially extended arm carried by said end of the shaft and extending in a plane approximately parallel with said plane of travel, the free end of said arm being connected with said door, a gear wheel on the other end of said shaft, an electric motor, and a reducing gearing connecting said motor and said gear wheel.

4. The combination with a car-door of an electric motor, an operating shaft driven thereby through reducing gearing, a radial arm normally connected with said shaft, but movable independently thereof, said arm

having a sliding connection with the door, a limit-switch for disabling the motor at each end of the door movement, and a torsion-switch operated by rotation of said shaft relative to said radial arm and controlling the motor circuit.

5. The combination with a car-door of an operating electric motor therefor and means for protecting passengers in the doorway, 10 comprising a switch controlling the motor circuit and means operated by the torsional stress of the motor for actuating said switch when the movement of the door is obstructed.

6. The combination with a car-door of a 15 reversible electric motor, means actuated by said motor for operating the door, said means including limit-switch contacts in each of the motor circuits for different directions of rotation, and a torsional-switch in the main circuit of the motor.

7. The combination with a car-door of an electric motor therefor, a radial arm acting on the door through a slide, a reducing gear between the motor and shaft of said arm, a 25 limit-switch and an independently controlled torsion-switch both arranged to control the motor circuit during the closing movement of the door.

8. The combination with a car-door of a 30 radial arm acting on the door through a slide, an electric motor, a shaft for the said arm, a second shaft driven by the motor through speed-reducing gearing, yielding devices normally connecting the two shafts and a switch operated by relative movement of said devices and controlling the motor circuit.

9. The combination with a car-door and its operating shaft, of an electric motor, a second shaft driven by the motor, connecting devices between the two shafts yieldable in either direction and a switch controlling the motor circuit operated by said devices.

10. The combination with a car-door of an 45 electric motor capable of operating the door when energized and of being reversely operated by pressure on the door when de-energized, and safety devices responding to obstruction of the door movement and acting to deenergize the motor and permit its reverse 50 operation by the door.

11. The combination with a car door of an operating electric motor permanently geared thereto and capable of being reversely operated by movement of the door in the reverse direction when de-energized, a limit-switch for deenergizing the motor at the end of the door-closing movement, and means whereby the door may be operated manually.

12. The combination with a rectilinearly 60 movable car-door of an operating electric motor therefor, a switch for closing the motor circuit for either direction of door-movement and limit-switch contacts in each of the 65 reversing circuits of the motor, said contacts

being operated by the respective door movements at the end thereof.

13. The combination with a car-door, of an operating electric motor for the door, a motor circuit, means actuated by said motor for operating the door, said means including a torsion-switch operated by the motor in the event of the door being obstructed and located in the motor circuit between the motor and the ground.

14. The combination with a car-door, of an electric motor, a spring between the motor and the door for reversing the motor when the latter is disabled and the door obstructed, and a controlling device for the motor normally inactive but acting to disable the motor on the yielding of said spring and to restore it when the spring is restored.

15. The combination with a car-door of an operating electric motor therefor, a spring 85 interposed between the motor and the door, said spring being normally unyielding but acting when under tension to mechanically reverse the motor if the latter is deenergized, and a switch for breaking the motor circuit 90 on the yielding of the spring.

Signed at Albany, county of Albany, and State of New York, this 8th day of March, 1922.
